UNITED STATES PATENT OFFICE.

HARRY A. DOUGLAS, OF CHICAGO, ILLINOIS.

CONNECTOR.

1,134,673.

specification of Letters Patent. Patented Apr. 6, 1915.

Application filed August 9, 1912. Serial No. 714,207.

To all whom it may concern:

Be it known that I, HARRY A. DOUGLAS, citizen of the United States, residing at Chicago, in the county of Cook and State of Illinois, have invented a certain new and useful Improvement in Connectors, of which the following is a full, clear, concise, and exact description, reference being had to the accompanying drawings, forming a part of this specification.

My invention relates to connectors employed for associating translating devices with sources of current.

My invention has a number of objects and advantages in view and the various features and advantages thereof will be fully disclosed by reference to the preferred embodiment of the invention shown by the accompanying drawing, but to which embodiment the invention is not to be limited.

In the drawing Figure 1 is a side elevation of a connector made in accordance with the preferred embodiment of the invention; Fig. 2 is a sectional view on line 2 2 of Fig. 1; Fig. 3 is a sectional view on line 3 3 of Fig. 1; Fig. 4 is a sectional view on line 4 4 of Fig. 1; Fig. 5 is a sectional elevation of the structure as it appears in Fig. 1; Fig. 6 is a sectional view on line 6 6 of Fig. 5, some parts being shown in complete plan; Fig. 7 is a view illustrating steps of manufacture which I preferably employ; and Fig. 8 illustrates a detail of construction.

Like parts are indicated by similar characters of reference throughout the different figures.

One feature of the invention resides in the mechanism employed for controlling the electrical association of two terminals *a* *b* which may, for example, be respectively connected with a source of current and a translating device or a conductor *c* leading to such translating device, though the invention is not to be limited to the association of the contacts *a* *b*. One of these contacts, the contact *b*, is pressed toward the other by a spring *d*, one contact being preferably countersunk while the other is partially tapered whereby thorough engagement between the contacts at their adjoining ends is assured. Some separating device is employed to operate longitudinally of the contacts *a* *b* for the purpose of causing these contacts to become separated when it is desired to open the circuit. This device may be in the form of a rod *e* of insulating material operating in a

bore or channel that is formed in the contact *a* for receiving it, this bore constituting a structural characteristic of the contact *a* that guides the rod *e* in its movement longitudinally of said contact. Some suitable means is employed for operating this rod to cause it to move longitudinally of the contact *a* for the purpose of forcing it against the contact *b* to move this contact *b* away from the contact *a* against the force of the spring *d*. A rod *f*, movable transversely of the direction of movement of the rod *e*, may be employed for the purpose. This rod *f* has seats *f*¹ *f*², the seat *f*² permitting sufficient rearward movement of the rod *e* to permit the spring *d* to force the contact *b* into firm electrical connection with the contact *a*. The seat *f*¹ is sufficiently shallow to hold the rod *e* in a position in which said rod is sufficiently thrust out to force the contact *b* away from the contact *a*. The adjacent walls of the seats *f*¹ *f*² are inclined as illustrated in Fig. 6 so that the rod *f* may readily be moved into either of its alternative positions in one of which the contacts *a* *b* are separated and in the other of which the contacts *a* *b* are in-engagement. In the preferred embodiment of the invention the contact *a* has a companion contact *g*, the contacts *a* and *g* being mounted in a cylindrical base portion or plug *h* of insulating material that carries a bayonet pin or projection *i*, this bayonet pin projecting at its ends beyond the base portion *h* so as to be receivable within bayonet slots *k* formed in a supporting shell *l* by outwardly bulging the shell. Thus the base *h* is insertible within and removable from the shell *l* upon being suitably turned as will be well understood by those skilled in the art. The contacts *a* and *g* are upon opposite sides of the axis of the base *h*. Hitherto it was proposed to modify the construction of the bayonet slots in a manner to permit rotation of the base *h* in one direction to an extent that would separate the contacts *a* and *g* from their opposing contacts *b* and *m* and in the reverse direction to effect proper engagement of the contacts *a* and *g* with their opposing contacts. By means of my invention the rotation of the base *h* is not required, the rods *e* and *f* performing the desired function without disturbing the mounting of said base. As the invention is embodied the contact *m* is also provided with a spring *n* for forcing it against its oppos-

ing contact *g*. The contacts *b* and *m* are shown as constituting spring pressed terminals of conducting cords *c* though the invention is not to be restricted to this association of these contacts.

Another feature of the invention resides in the construction illustrated in Figs. 5 and 8. In forming contacts *b* and *m* little burs or minor projections *o* are likely to be formed upon the ends of said contacts and where these ends have butt engagement with other contacts heating of the equipment is likely to result owing to the reduced contact at *o*. It is one object of my invention to provide means for preventing the projections *o* from having engagement with the opposing contacts and to this end I provide such opposing contacts with bores for receiving the projections *o*, the bore of the contact *a* being suitable for this purpose while an especially provided bore *p* in the contact *g* also serves the purpose. The mouths of these bores are desirably flared while the opposing ends of the contacts are of corresponding truncated cone formation whereby the area of contact lost by the formation of the bores is replaced.

Another feature of the invention resides in the shell *l* and the bayonet slots or recesses formed therein. This shell is provided with a flange *q* integrally formed therewith. The bayonet slots *k* have the portions thereof which are disposed longitudinally of the shell continued through the flange *q*, these portions of these bayonet slots being in the form of outsetting depressions that are shaped in the cylindrical wall of the shell, the bayonet slots being in the form of enlargements of the shell bore. The bayonet slots or recesses do not extend through the shell and as the shell and the flange are of integral formation there is no opportunity for leakage of moisture transversely of the shell through its cylindrical wall. Thus when the parts are assembled, as shown in Fig. 5, water does not have opportunity of finding its way through the shell except by passage longitudinally thereof through its bayonet slots and the ends of the shell, a possibility which is reduced to the minimum by the insulating base *h* which tightly fills one end of the shell and the plug *r* of insulating material that carries the contacts *b* at the other end of the shell. As the invention is embodied the plug *d* also serves to carry terminals *s* of conductors *c*, these terminals carrying the springs *d* and *n* for the purpose which has been described. In order to reduce to the minimum the possibility of the flow of water through the shell *l* the base *h* is made sufficiently long to project inwardly beyond the bayonet recesses or slots *k*.

Another feature of my invention relates to the angle or elbow joint, a form of which

is shown in Figs. 1 and 5 and a step in the manufacture of which is illustrated in Fig. 7. The base or plug *h* constitutes one member of the joint, the external portion of this plug being suitably formed to constitute it such member. The complementary member *t* of the joint is inclined with respect to the joint member *h*, these two members being mitered. One or two angle rods or bolts *u* have sliding fit within holes provided in the joint members *h* and *t*, one arm of each rod or bolt *u* being received within one member while the remaining arms are received within the other member. The contacts *a* and *g* are in threaded engagement with adjacent ends of the bolts *u* and constitute preferred means whereby these bolts are held in fixed connection with the joint member *h*. Terminals *v* are in threaded engagement with the arms of the bolts that are received by the joint member *t* and constitute preferred means whereby the bolts are held in fixed engagement with the latter joint member. As the invention is preferably practised the terminals *v* and the adjacent ends of the bolts *u* are in normally fixed relation with the joint *t* while the contacts *a* and *g* are provided at their outer ends with screw-driver slots (one being indicated at *w* in Fig. 8) whereby these contacts may be screwed into and out of engagement with the ends of the bolts *u* that are in sliding engagement with holes in the joint member *h*. By screwing the nuts *a* and *g* upon the corresponding ends of the bolts *u* the joint members *h* and *t* are drawn tightly together. The protecting sleeve cap *x* is screwed upon the outer end of the joint member *t* and is provided with a bore through which the conductors *y* are passed for connection with the contacts *v*. The circuit between the conductors *y* and the contacts *a* and *g* is traced through the terminals *v* and the rods *u*.

While I have herein shown and particularly described the preferred embodiment of my invention, I do not wish to be limited to the precise details of construction shown nor to the employment of all the characteristics in an electrical connector. I use the term "electrical connector" in a broad sense as I do not desire to limit the use of the device to a portion of a circuit comparatively remote from the source of current and the translating device supplied thereby, since it is obvious that the invention will be realized without regard to the location of the contacts *a* *b* *g* *m* with respect to the source of current and the translating device. In one view of the invention the contacts *b* and *m* may be said to constitute terminals of a translating device and the contacts *a* and *g* may be said to constitute terminals of a source of current.

Having thus described my invention I

claim as new and desire to secure by Letters Patent the following:—

1. An electrical connector including two aligned contacts; a spring for pressing one contact against the other, the latter contact having a channel; a rod operating in said channel for engaging the spring pressed contact to move it out of electrical connection with the contact having the channel; and a second rod movable longitudinally of itself and transversely of the direction of movement of the first rod and having seats of differing depths, one for positioning the first rod to maintain the contacts in separation and the other to permit the first rod to be so positioned that said spring may effect engagement between the contacts.
2. An electrical connector including two aligned contacts; a spring for pressing one

contact against the other; a rod operating longitudinally of the contact for engaging the spring pressed contact to move it out of electrical connection with its companion; and a second rod movable longitudinally of itself and transversely of the direction of movement of the first rod and having seats of differing depths, one for positioning the first rod to maintain the contacts in separation and the other to permit the first rod to be so positioned that said spring may effect engagement between the contacts.

In witness whereof, I hereunto subscribe my name this seventh day of August A. D., 1912.

HARRY A. DOUGLAS.
